COMPENSATION DEVICE FOR MISALIGNED DEFLECTION PLATES IN CATHODE RAY TUBES

Thomas H. Tatham, Jr., San Diego, Calif., assignor to General Dynamics Corporation, Rochester, N.Y., a corporation of Delaware

Application September 30, 1958, Serial No. 764,388

8 Claims. (Cl. 315—24)

The present invention pertains to a compensation device for misaligned electrostatic deflection plates in cathode ray tubes and more specifically, concerns an electrical circuit which substantially eliminates distortion in cathode ray tube displays caused by electrostatic plates not being properly aligned.

In cathode ray tubes, the electro-responsive screen, on which the electron beam creates image displays, may be referred to in terms of an X—Y coordinate plot, with the X axis called the horizontal axis and the Y axis called the vertical axis. Electrostatic deflection plates positioned in pairs in a quadrature arrangement in the neck of cathode ray tubes function to deflect the electron beam relative to the screen along the aforesaid horizontal axis or vertical axis or in combinations of the two. Each plate of a pair of electrostatic deflection plates, when correctly aligned, lies in a plane that is parallel with but displaced from the other plate of the respective pair. The pair of plates are normally positioned at a 90° angle with another pair of plates giving the quadrature arrangement. This normal arrangement of pairs of electrostatic deflection plates is shown in Patent No. 2,829,302 to Thomas H. Tatham and assigned to the common assignee hereof.

In inserting and securing pairs of electrostatic plates in the neck of cathode ray tubes, it is many times difficult to correctly align the pairs of plates so that the respective planes of each pair are at the desired 90° angle to the plane of the other pair, thereby giving the quadrature relationship. This difficulty arises because minor misalignment of the plates may only become apparent after the cathode ray tube is completely assembled and operating, at which time the plates are inaccessible for adjustment. The misalignment condition that is normally encountered is where one pair of plates lies in a plane that is at an angle other than 90° with respect to the common plane of the other pair of plates. This causes the quadrature relationship of the pairs of plates to have a rhombic orientation rather than a square orientation. When the pairs of electrostatic deflection plates have a rhombic relationship they are then incapable, through normal separate signal control, of correctly deflecting an electron beam along either the horizontal or vertical axis of the cathode ray tube, or combinations of the two.

The misalignment of electrostatic deflection plates in their quadrature or orthogonal positioning in the neck of cathode ray tubes is a problem of long standing. The effects of this misalignment in the deflection of the electron beam can be detrimental to the orientation of display on the screen of a cathode ray tube. In those cathode ray tubes which utilize a moving spot for creating displays, such misalignment of electrostatic deflection plates can cause the displayed picture to have a slanted appearance, since the electron beam may not be deflected on a true vertical or horizontal axis line. In the type of cathode ray tubes known as shaped beam cathode ray tubes, the misalignment of electrostatic de-

2

flection plates can be extremely detrimental as it causes distortions in the display of the character images.

Shaped beam cathode ray tubes use an electron beam that has a relatively large cross-sectional area which is shaped by a beam shaping matrix into character images. This character shaped electron beam when contacting the electro-responsive screen causes an image on the screen to be illuminated having the character shape. Should an electron beam of the shaped beam type be deflected by misaligned electrostatic deflection plates, the character image of the electron beam will be rolled over, slanted or otherwise distorted, and will, accordingly, cause to be displayed on the screen of the tube a distorted character image which may have the general shape of a parallelogram or rhombic figure. This, of course, is detrimental to the quality of the display as it detracts from its legibility and desirability. Accordingly, a need exists for the present invention to provide a simple circuit arrangement capable of correcting this misalignment of the electrostatic deflection plates, inasmuch as it is quite difficult to provide correctly aligned electrostatic deflection plates in the neck of the cathode ray tube and still maintain large volume production of such tubes.

It is accordingly an object of this invention to provide a circuit to be used in combination with cathode ray tubes that is capable of substantially eliminating distortions that may occur from electrostatic deflection plates that are not properly aligned.

In accordance with the present invention, when the condition exists in a cathode ray tube wherein one pair of electrostatic deflection plates is positioned askew, circuit means are provided which supply a correcting potential to the misaligned plates creating an electrostatic field between the plates capable of deflecting the electron beam in a manner as if the plates were correctly aligned. The circuit means includes a summing amplifier circuit that may be placed in one of the lines carrying the control signals from the source to the deflection plates. This circuit means receives the control signals that would normally be applied to the deflection plates and provides a corrected potential output to the misaligned pair of plates having a magnitude which compensates, in deflecting the beam, for the misalignment of the electrostatic plates. The corrected potential has a magnitude that reflects changes in the magnitude of the control signals supplied to the other pair of electrostatic deflection plates, which plates taken with the misaligned pair comprises the aforesaid quadrature arrangement. A potentiometer means is incorporated in this circuit means for providing selective adjustment of the magnitude of the signal received by the misaligned pair of plates in response to changes in the deflection potential applied to the other set of electrostatic deflection plates. Accordingly, in the present invention voltages may be selectively taken from the signals applied to one set of plates and added to the signals applied to the other incorrectly aligned set of plates, thereby correcting the resultant deflection of the electron beam by the incorrectly aligned plates to correspond with the deflection of the beam that may be expected from a correctly aligned pair of plates.

The exact nature of this invention as well as other objects and advantages thereof will be readily apparent from consideration of the following specification relating to the annexed drawings in which:

Figure 1 is a perspective view of a shaped beam cathode ray tube;

Figure 2 is a schematic illustration of the circuit arrangement for practicing the present invention; and

Figure 3 illustrates the display screen of a cathode ray

tube with the distorted display and the corrected display illustrated thereon.

Referring more particularly to the drawings, wherein like reference numerals refer to the same parts throughout the several views, in Figure 1, a cathode ray tube 5 of the shaped beam type is shown. This type of tube utilizes electrostatic deflection plates for deflecting the electron beam at several points along its path from the beam generating and projecting unit 14 to the electro-responsive screen 13 in a manner disclosed in Patent No. 2,735,956, issued to Joseph T. McNaney and assigned to the same assignee hereof. Shaped beam tubes project a diffused type electron beam which, because of its relatively large cross sectional area, may be shaped to desired character images. Because the electron beam normally has a larger cross sectional area than that encountered in ordinary cathode ray tubes, the misalignment problems in placing electrostatic deflection plates in shaped beam cathode ray tubes is greater. Further inasmuch as the electron beam is shaped into character images the misalignment of electrostatic deflection plates can result in a slanted character image on the screen of the tube which is obviously undesirable. In tubes of this type as well as other cathode ray tubes, sets of electrostatic plates such as sets 6, 7 and 8, function to deflect an electron beam in an X, Y plane that is perpendicular to the longitudinal axis of the tube. These sets of plates may be utilized to deflect the electron beam at selective points along the neck of the tube or for finally positioning the beam's point of impact with the electro-responsive screen 13.

The misalignment condition of a set of plates will result in a deflection of the electron beam, when the electrostatic plates receive the correct potential, in a manner causing distortion in the final display on the screen of the cathode ray tube. With reference to Figure 2, the electrostatic deflection plates shown schematically therein are in a normally encountered position of misalignment wherein the pair of electrostatic plates 11 are in the correct horizontal alignment and electrostatic plates 12 are misaligned in a direction oblique to the desired vertical deflection line.

When the electron beam is projected from the beam generating means 14 in a path along the longitudinal axis of the cathode ray tube 5 and is deflected by the misaligned plates 12 as shown in Figure 2, which could also be the pair of the set of plates 8 shown in Figure 1, the beam will be deflected correctly along the horizontal line 15. However, when the beam is deflected by correctly aligned plates 11, it will be deflected incorrectly along line 17 in the vertical direction. Therefore when the beam is deflected in a vertical direction in any of the four X, Y, quadrants it will be deflected at an angle to the vertical axis 16 that corresponds substantially to line 17. The degree of variance from the vertical line 16 is dependent upon the amount of misalignment of the misaligned plates. The deflection of the beam along the horizontal line 15 will be substantially correct inasmuch as electrostatic deflection plates 11 are positioned parallel to the horizontal axis line 15. Therefore, when the beam is caused to be deflected in a horizontal direction by a voltage change on electrostatic deflection plates 12 only, it will maintain its correct position in a horizontal plane because it will maintain the same relative spacing between the plates 11 in its horizontal path, and the deflecting influence of the field between plates 11 will remain the same. However, when the electron beam is deflected in a vertical direction by a change in the potential on electrostatic plates 11, the beam will be caused to be moved not only in a vertical direction, but also to a certain degree in a horizontal direction, giving a resultant direction of deflection that lies substantially along line 17. This condition results inasmuch as the beam's relative distance between plates 12 is moving in a direction other than the vertical direction along line 16. Thus for the

beam to maintain the same potential relationship between plates 12, it must move on a line substantially parallel to the plates 12. Accordingly, it may be expected when the plates are misaligned as shown in Figure 2, that any direct deflection in the vertical direction will not follow a vertical path but rather will follow a path substantially parallel to the misaligned plates.

The circuit arrangement disclosed in Figure 2 operates substantially as follows. Control signals are supplied in the form of voltages to the electrostatic deflection plates 11 and 12 from the source of control signals as shown. The normal supply voltage signal that would be supplied to electrostatic deflection plates 12 from the source of control signals, if they were correctly aligned, is the voltage E_1 which is supplied to line 19. The normal supply voltage supplied to electrostatic plates 11 is the potential E_2 which is supplied to line 18. Since the plates 12 are misaligned, as shown in Figure 2, the beam when deflected moves in a vertical direction along line 17. To correct this, circuitry including a summing amplifier 24 is inserted into the line 19. The summing amplifier 24 operates as stated on page 664, Figures 18-49 in "Electronic and Radio Engineering" by Frederick E. Turman, published by McGraw-Hill in 1955, and is capable of summing two or more voltage waves and providing an output voltage that is proportional to the sum of the independent voltages supplied to the summing amplifier. Because of the feed-back arrangement in the summing amplifier, it constitutes substantially a zero impedance. Accordingly, the output voltage is substantially immune to minor variations in changes in the input voltage.

Voltage E_1 is supplied to the summing amplifier through limiting resistor 20 as voltage E_4 . A portion of voltage E_2 , that is supplied directly to the horizontal deflection plates 11, is tapped off by potentiometer 21 providing a voltage E_3 through limiting resistor 23 to the summing amplifier 24. By varying potentiometer 21, the magnitude of the potential E_3 may be varied as desired. Generally the limiting resistors 20 and 23 have substantially the same resistance values. The output voltage E_5 to the misaligned plates 12 has a magnitude that is proportional to the sum of input voltages E_3 and E_4 . Accordingly, the potential on electrostatic plates 12 is dependent upon the input potential E_1 and the tapped off voltage E_3 . Inasmuch as the tapped off voltage E_3 is proportional to the magnitude of the voltage E_2 in line 18, the voltage E_5 thus reflects any changes in the potential E_2 that is applied to electrostatic deflection plates 11.

For example if initially the drop across the pair of plates 11 is 10 volts and the drop across the pair of plates 12 is 10 volts, the electron beam may be caused to strike the screen 37, see Figure 3, of a cathode ray tube at point 31. If in this situation the potential drop across plates 11 is increased to 20 volts and the potential across plates 12 held at 10 volts, the beam would then strike the screen 37 at point 32. However, in accordance with the invention, the aforesaid circuit arrangement would cause the voltage drop across plates 12 to increase from 10 volts to 12 volts. This increase would cause the electron beam to strike the screen at point 33, which, as desired, is along the vertical axis. Therefore, when the potential on electrostatic deflection plates 11 is increased, the potential on electrostatic deflection plates 12 is also increased. Conversely when the potential on electrostatic deflection plates 11 is decreased, the potential on electrostatic deflection plates 12 is also decreased.

The aforesaid circuit and voltage arrangement causes the electron beam to be deflected in a correct vertical direction 34 and horizontal direction 35, as shown in Figure 3, rather than along the oblique line 36 with the accompanying distortion in the character images.

In Figure 2 if E_5 , the potential applied to electrostatic deflection plates 12, is varied by varying E_1 and E_2 is held constant, the beam will then be deflected in a horizontal direction with no change in its deflection resulting from

the addition of the voltage E_3 inasmuch as potential E_2 has not been altered. However, if the potential E_2 is varied and potential E_1 remains constant, the output voltage E_5 is then varied in magnitude in proportion to the change of the potential magnitude E_2 , which results in E_5 being increased in accordance with the increase in value of potential E_3 . Potentiometer 21 provides an external and easily accessible means for varying the value of E_3 and thus establishing by direct view of the screen when the cathode ray tube is in operation, the amount of potential needed to provide a correct vertical deflection of the beam under most circumstances. Accordingly, when E_3 is set to the correct range, then any deflection of the beam in the vertical direction due solely to changes in the potential across plates 11 will be along the vertical line 16 as shown in Figures 2 and 3.

While in the instant exemplification, the horizontal plates 12 are shown in a misaligned arrangement; the converse could be true where the vertical plates 11 would be misaligned and the horizontal plates 12 would be in a direction parallel to the vertical line 16. Also, the device would operate when both the horizontal and vertical plates may be misaligned at which point two summing amplifiers would be present, one in each of lines 18 and 19 and could be so correlated as to provide a correct vertical and horizontal deflection of the beam regardless of the potential applied to the respective plates.

Obviously many modifications and variations of the present invention are possible in the light of the above teachings. It is therefore to be understood, that within the scope of the appended claims, the invention may be practiced otherwise than as specifically described.

I claim:

1. In a cathode ray tube display system wherein an electron beam is deflected to predetermined positions on the screen of the cathode ray tube in accordance with X-Y potentials being applied to pairs of electrostatic deflection plates when one of the pairs of plates may be positioned askew, the improvement comprising adjustable summing amplifier means for varying the potential supplied to the askew pair of plates in response to variations in the magnitude of the potentials applied to the other pair of said deflection plates.

2. In a cathode ray tube display system wherein an electron beam is deflected to predetermined positions on the screen of the cathode ray tube in accordance with deflection potentials being applied to pairs of electrostatic deflection plates from a source of control signals, when one of the sets of plates may be positioned askew, the improvement comprising summing amplifier means for receiving potentials from said source of control signals and providing an adjustable output signal to said askew set of deflection plates, said output signal having a magnitude corresponding to the sum of the magnitude of the signal normally applied to the askew deflection plates from said source of control signals and the magnitude of a second pulse which varies in accordance with the magnitude of the potential applied to said other set of plates from said source of control signals but of a lesser ratio of magnitude, a potentiometer being positioned between said other set of deflection plates and said summing amplifier for selectively adjusting the magnitude of said signal received from said other deflection plates in response to the change in the deflection potentials applied to said other set of said deflection plates.

3. In a cathode ray tube display system wherein an electron beam is deflected to predetermined positions on the screen of the cathode ray tube in accordance with deflection potentials being applied to pairs of electrostatic deflection plates when one of said pairs of electrostatic deflection plates may be positioned askew while other of said pairs of electrostatic deflection plates may be correctly aligned, the improvement comprising summing

amplifier means responsive to the magnitude of deflection control signals supplied to said correctly aligned pair of deflection plates for applying a corrected deflection signal magnitude to said pair of askew plates.

- 5 4. In a cathode ray tube display means having deflection means responsive to control signals for deflecting an electron beam to predetermined positions on the screen of a cathode ray tube wherein the deflection means includes two pairs of electrostatic deflection plates positioned in the form of a rhombus with one pair having substantially a correct alignment and the other pair having an incorrect alignment, the improvement comprising a summing amplifier for combining a portion of a control signal to said correctly aligned plates with a control signal to said incorrectly aligned plates, providing an output signal to said incorrectly aligned plates having a magnitude that varies in accordance with the deflection magnitude of said control signal to said incorrectly aligned plates and the magnitude of the deflection signal to said correctly aligned plates.
- 10 5. In a cathode ray tube having beam generating means for generating and projecting an electron beam toward an electro-responsive screen and deflection means for deflecting said beam, said deflection means including a pair of misaligned electrostatic plates and a pair of correctly aligned electrostatic plates, a source of first control signals for supplying separate deflection signals to each of said pairs of plates, summing amplifier means responsive to the magnitude of control signals to both of said 30 pairs of deflection plates for providing second control signals to said misaligned pair of plates having a magnitude that varies with the magnitude of said first control signals to both of said pairs of plates.
- 35 6. In a system for displaying characters on screens of cathode ray tubes including a shaped beam cathode ray tube having deflection plates for positioning a shaped electron beam relative to the longitudinal axis of said shaped beam cathode ray tube, the improvement comprising summing amplifier means for providing control signals to one of said plates of said deflection means, said control signals having a magnitude that varies in correspondence with the magnitude of the control signal applied to other of said deflection plates.
- 40 7. In a cathode ray tube display system wherein an electron beam is deflected by pairs of electrostatic deflection plates in accordance with X-Y potentials being applied to said pairs of electrostatic deflection plates positioned in quadrature when one of said pairs of plates may be positioned at an angle other than 90° relative to 50 the other of said pairs of plates, the improvement comprising summing amplifier means for varying the potential applied to one pair of said plates in proportion to variations in the magnitude of potentials applied to the other pair of said deflection plates for causing said electron beam to be deflected in a desired X-Y plot irrespective of angular positioning of one of said pair of plates relative to the other of said pair of plates.
- 55 8. In combination a cathode ray tube display system having electrostatic deflection means for deflecting an electron beam, said deflection means being positioned in misalignment, summing amplifier means for receiving portions or control signals supplied to said deflection means for providing new control signals to said deflection means, said deflection means in response to said new control signals deflecting said beam in a manner similar to that deflection of an electron beam that would occur if said deflection system had been correctly aligned.
- 60 9. In a cathode ray tube display system having electrostatic deflection means for deflecting an electron beam, said deflection means being positioned in misalignment, summing amplifier means for receiving portions or control signals supplied to said deflection means for providing new control signals to said deflection means, said deflection means in response to said new control signals deflecting said beam in a manner similar to that deflection of an electron beam that would occur if said deflection system had been correctly aligned.
